HEAT CONDUCTING SKEWER

Paul K. Dawson, Los Angeles, Calif.

Application April 30, 1956, Serial No. 41,248

Term of patent 14 years

(Cl. D44—29)

Figure 1 is a plan view of a heat conducting skewer; Fig. 2 is a side elevation thereof;

Figs. 3 and 4 are end views, taken in the direction of the arrows 3 and 4 of Fig. 1; and

Fig. 5 is an enlarged sectional view, taken along a plane indicated by line 5—5 of Fig. 1.

I claim:

The ornamental design for a heat conducting skewer, substantially as shown.
